HOLDING AND SQUEEZING MECHANISM
FOR PASTE TUBES

Joseph S. Clark, Baltimore, Md.

Application May 25, 1931, Serial No. 539,886
Renewed February 28, 1933

14 Claims. (Cl. 221—60)

My invention relates to holding and squeezing devices for paste tubes.

The principal object of my invention is to provide a device for holding and squeezing collapsible containers carrying a substance which it is desired to discharge through an opening therein.

A further object of the invention is to provide a device which may be attached to or taken from the wall or other surface as the need arises. And the invention has a still further object to provide a device of this character wherein the means for attaching will not be seen.

A further object of the invention is to provide a simple, inexpensive and a thoroughly practicable device that will actually do all that is claimed for it.

These and further objects of the invention will be set forth in the following specification, reference being had to the accompanying drawing, and the novel means by which said objects are effectuated will be definitely pointed out in the claims.

In the drawing:

Fig. 1 is a perspective view showing a tube suspended between the squeezing mechanism.

Fig. 2 is a transverse sectional view of the invention, taken on the line 2—2, as shown in Fig. 1;

Fig. 3 is a bottom view showing one form of squeezing mechanism, the slots in the frame member for attaching to the wall and the grooves and key holes for the apron or shield.

Fig. 4 is a perspective view of the apron or shield.

Fig. 5 is a perspective view of a modified form of slotted roller.

Fig. 5a is another modified form of slotted roller showing a hard core and a resilient body.

Fig. 6 is another bottom view showing a tube being drawn between the slotted roller and the front end of the frame member.

Referring to the drawing, 1 indicates the body or frame member which may be made of any suitable material, the sides having apertures for accommodating the spindles 2 and 3 on which the rollers 4 and 5 are mounted. The lower portion of the back 6 has two or more slots. These slots slip over and around the screws 7 which, when tightened, hold the body to the wall. The trunnions 8 and 9 support the apron or shield 10 between the sides of the body in the key holes 11 and 12. The slotted roller 4 which is preferably all metal has an extended trunnion 13 which is also slotted to admit the thumb piece 14. When the flattened end of the tube is inserted in the slotted roller and the thumb piece turned the tube

is drawn between the squeezing mechanism as in Figs. 2 and 6 and the contents forced out. The flange 36 of the frame member 38 is rolled sufficiently to allow the tube 40 to pass yet retarding the tube sufficiently to cause it to wrap tightly around the pulling roller which causes a pressure of the tube against the roller which in turn forces out the contents. The squeezing member 5 in Fig. 3 may be either a roller or a stationary yielding body, which will allow for the additional space required between the squeezing members as the used portion of the tube is wound around the pulling roller 4. The surface of the slotted roller is preferably roughened so that when the roller is reversed the empty tube will be discharged. The apron or shield 10 is held in place by the trunnions 8 and 9 which fit in the key holes 11 and 12. The apron or shield as shown in Fig. 4 is to conceal the screws or manner of supporting the frame member as well as being used for a guide to prevent the used portion of the tube curling around and wedging between the squeezing mechanism when a slotted roller is not used. Fig. 5 shows a modified form of the slotted roller which may be constructed with a hard surface and yielding core or bearing 21, which supports the trunnions 24; or, as shown in Fig. 5a, the outside surface may be of a yielding material and the bearings or core 21 of a hard substance, supporting the trunnions 24. Either of these structures will give sufficiently to permit the used portion of the tube to be wound around and between the roller and its adjacent squeezing member.

I claim:

1. Means for supporting and compressing a collapsible tube, comprising a curved, substantially cup shaped frame member having substantially parallel end walls, squeezing mechanism comprising a slotted roller, the ends of which are rotatably journaled in bearings in said parallel walls adjacent the open end of said cup shaped frame member. A curved surface associated with said frame member adjacent to and in fixed position relative to said roller, said roller co-operating with said adjacent curved surface for compressing the tube.

2. Means for supporting and compressing a collapsible tube, comprising a frame member having substantially parallel end walls, squeezing mechanism consisting of a slotted roller, the ends of which are rotatably journaled in bearings in said walls, a rigid parallel compressing member associated with said frame member adjacent to and in fixed position relative to said roller, said roller co-operating with said adjacent rigid par-

allel compressing member for compressing the tube.

3. Means for supporting and compressing a collapsible tube, comprising a frame member having substantially parallel end walls, squeezing mechanism consisting of a slotted roller, the ends of which are rotatably journaled in bearings in said walls, a compressing member associated with said frame member adjacent to and in fixed position relative to said roller, said roller co-operating with said adjacent compressing member for compressing the tube, and an apron or shield mounted in said frame member to conceal the screws supporting the mechanism.

4. Means for supporting and compressing a collapsible tube, comprising a frame member having substantially parallel end walls, squeezing mechanism comprising a slotted roller, the ends of which are rotatably journaled in bearings in said walls, a rigid parallel compressing member associated with said frame member adjacent to and in fixed position relative to said roller, said roller having the outer surface of rubber or other suitable material which will give sufficiently to allow the used portion of the tube to be wound around and between the roller and the adjacent rigid parallel compressing member.

5. Means for supporting and compressing a collapsible tube, comprising a frame member having substantially parallel end walls, squeezing mechanism comprising a fixed yielding or resilient roller, the ends of which are rotatably journaled in bearings in said walls, a rigid parallel compressing member associated with said frame member adjacent to and in fixed position relative to said roller, said roller co-operating with said adjacent rigid parallel compressing member for compressing the tube.

6. Means for supporting and compressing a collapsible tube, comprising a frame member having substantially parallel end walls, squeezing mechanism comprising a slotted roller, the ends of which are rotatably journaled in bearings in said walls, said roller co-operating with an adjacent roller, mounted in parallel relation to said slotted roller to securely hold and compress a collapsible tube at least one of the rollers having its outer surface rubber or other giving material so as to compress the tube tighter and yet allow for the passing of the used portion of the tube as it is wound around the pulling roller.

7. Means for supporting and compressing a collapsible tube, comprising a frame member having substantially parallel end walls, squeezing mechanism comprising a slotted roller, the ends of which are rotatably journaled in bearings in said walls, said roller co-operating with an adjacent roller, mounted in parallel relation to said slotted roller to securely hold and compress a collapsible tube at least one of the rollers having a hard surface with a resilient core between said hard surface and the supporting spindle.

8. Means for supporting and compressing a collapsible tube, comprising a frame member having substantially parallel end walls, squeezing mechanism comprising a pair of rollers, at least one of said rollers being slotted, the ends of which are rotatably journaled in bearings in said walls, said rollers co-operating to securely hold and compress a collapsible tube, at least one of the rollers being composed of yielding or resilient substance and a hard core or trunnions which support the roller.

9. Means for supporting and compressing a collapsible tube, comprising a frame member hav-

ing substantially parallel end walls, squeezing mechanism comprising a slotted roller, the ends of which are rotatably journaled in bearings in said walls, a compressing member associated with said frame member adjacent to and in fixed position relative to said roller, said roller co-operating with said adjacent compressing member for compressing the tube, said roller having a hard surface with a resilient core between said hard surface and the supporting spindle.

10. Means for supporting and compressing a collapsible tube, comprising a frame member having substantially parallel end walls, squeezing mechanism comprising a slotted roller, the ends of which are rotatably journaled in bearings in said walls, a compressing member associated with said frame member adjacent to and in fixed position relative to said roller, said roller co-operating with said adjacent compressing member for compressing the tube, said roller having a yielding or resilient surface and a hard core or trunnions which support the roller in said frame member.

11. Means for supporting and compressing a collapsible tube, comprising a frame member having substantially parallel end walls, squeezing mechanism comprising a slotted roller mounted in said end walls, a compressing member associated with said frame member adjacent to and in fixed position relative to said roller, said roller co-operating with said adjacent compressing member for compressing the tube, and an apron or shield mounted in said frame member to conceal the screws supporting the mechanism or frame member.

12. Means for supporting and compressing a collapsible tube, comprising a frame member having substantially parallel end walls, squeezing mechanism comprising a pair of rollers, at least one of the rollers being slotted, the ends of which are rotatably journaled in bearings in said walls, said rollers co-operating to securely hold and compress a collapsible tube, at least one of the rollers being composed of a yielding or resilient substance and a hard core or trunnions which support the roller, and an apron or shield mounted in said frame member to conceal the screws supporting the mechanism or frame member.

13. Means for supporting and compressing a collapsible tube, comprising a frame member having substantially parallel end walls, squeezing mechanism comprising a pair of rollers, at least one of the rollers being slotted, the ends of which are rotatably journaled in bearings in said walls, said rollers co-operating to securely hold and compress a collapsible tube, at least one of the rollers being composed of a hard surface with a resilient core between said hard surface and the supporting spindle, and an apron or shield mounted in said frame member to conceal the screws supporting the mechanism or frame member.

14. Means for supporting and compressing a collapsible tube, comprising a substantially cup shaped frame member having substantially parallel end walls, squeezing mechanism comprising a slotted roller, the ends of which are rotatably journaled in bearings in said parallel walls adjacent the open end of said cup shaped frame member, a compressing member associated with said frame member adjacent to and in fixed parallel position relative to said roller, said roller co-operating with said adjacent compressing member for compressing the tube.
